ATTORNEYS.

UNITED STATES PATENT OFFICE

JOHN C. STOKES, OF HOUSTON, TEXAS

DRILL BIT

Application filed October 19, 1929. Serial No. 400,952.

This invention relates to improvements in drill bits and a method of constructing the same.

In conventional drill bit construction, it is ordinary practice to attach the blade to the bit body by means of bolts. The bolts sometimes work loose and permit the blade to vibrate upon the body, resulting sometimes in the destruction of the bit structure, and inefficiently performing the drilling operation. A usual type of bit construction using a fish-tail blade, is to provide a slot longitudinally at the lower end of the bit body, wherein the blade fits, and is secured by transverse bolts. The disadvantages above mentioned are also present in such structure. To overcome them I have provided a bit structure wherein the body receives the bit blade in a bolted relation within the slot thereof; a sufficient clearance being provided between walls of the slot and the blade for receiving a metal which is fusible at a lower temperature than the material of the bit body or blade, to provide a tight anchoring fit of the blade in the body.

A further object of the invention is the provision of an improved drill bit construction as above mentioned, with the addition of transverse anchoring pins secured to the bit blade in a relation to be anchored within the bit body, by the easily fusible metal, in an efficiently anchored relation.

Other objects and advantages of this invention will be apparent during the course of the following detailed description.

In the drawings, wherein for the purpose of illustration is shown only a preferred embodiment of the invention,

Figure 1 is a sectional view taken longitudinally of the bit structure, showing more particularly the initial assemblage operation of the fish-tail blade in the bit body, prior to receiving the fusible metal for anchoring purposes.

Figures 2 and 3 are sectional views taken substantially on their respective lines in Figure 1 of the drawing.

Figure 4 is a view of the bit construction showing it assembled upon a drill stem.

Figure 5 is a sectional view taken substantially on the line 5—5 of Figure 6.

Figure 6 is a view similar to Figure 1, with the bit blade and other details anchored in place in the body by means of the fusible metal.

Figure 7 is a sectional view taken substantially on the line 7—7 of Figure 6.

In the drawings, wherein similar reference characters designate corresponding parts throughout the several views, the letter A may generally designate the improved bit assemblage, as shown in Figures 4 and 6, which includes the bit body B, receiving the blade C in an anchored relation on the body B, by means D.

The main body part B preferably includes the lower thin, but relatively wide part 10, having an upwardly tapered externally screw threaded coupling portion or shank 11 thereon, which is adapted for detachable threading in a quick release or attaching relation within a screw threaded socket 12 provided in the lower end of the drill line section 13, as shown in Figure 4. The body 10 of the main body part B is provided with a slot 20, opening at the lower surface 21 thereof, and extending from side to side across the width of said body part 10, as is shown in Figures 1 and 2 of the drawings. This slot 20 may be of any depth longitudinally of the main body B, and it is adapted to receive the upper flat portion 25 of the fish-tail bit blade C, which may be of usual construction, having the lower bit ends 26 thereon. The body 25 of the blade structure C is provided with a transverse centrally located passageway or opening 28 therethrough, and at each side of the opening 28 there are also provided tapered transversely extending openings 29, which taper in the same relation from one face of the body 25 to the other face thereof, as is well shown in Figure 2 of the drawing.

The bifurcated lower end of the main body B is provided with a transverse passageway 31, intersecting the slot 20 about midway between the side edges of the said main body B, as shown in Figure 2, which receives a detachable bolt 32; the shank 33 thereof extending thru the aperture 28 of the blade C to

hold the latter. The head 34 of the bolt 32 of course rests against one face of the body B, and the opposite screw threaded end receives a detachable nut 35 held against removal by a cotter pin 36.

The bifurcated lower end of the main body B, at opposite sides of the passageway 31, and in alignment with the tapered opening 29 of the bit blade, when the latter is assembled in the slot 20, are provided with transverse openings. As shown in Figure 2, the depending flanges, at opposite sides of the slot 20, for each tapered opening 29, are provided with openings 39 and 40; the former being tapered divergently from the outer face 41 of the respective flange of the body B in which they are provided, towards the slot 20. The opening 40 may be of uniform diameter. When the blade C is in position, the openings 29, 39 and 40 axially align.

Preferably solid tapered anchor pins 45 are driven into the tapered openings 29 of the blade construction C, after the latter is assembled and held in place in the slot 20 by the bolt 32; the said pins 45 being entered through the openings 39, with their smaller ends first, so that when driven firmly into the tapered openings 29 the smaller and larger ends of the tapered pins 45 will project beyond opposite sides of the blade body into the openings 40 and 39 respectively, as shown in Figure 2; said pins 45 being only of such length that the ends thereof will not project beyond the outer faces of the main body portion 10 in which the blade is positioned, as shown in Figure 2.

It is to be particularly noted that no machining of the inside surfaces of the slot 20, nor of the openings through the main body 40 or blade are necessary, nor are the opposite faces of the blade shank machined. Rather, they are left roughened. Clearances are provided between the facing surfaces of the blade C, and the main body B, and also between the extension ends of the pins 45 in the openings 39 and 40. In these clearances, after assemblage of the parts to the extent above described, there is poured molten metal, which is fusible at a temperature less than the tempering heat of the main body or blade. Such metal may be ordinary solder, babbitt, or Monel metal of well known characteristics. All of the clearances are filled to the extent shown in Figures 5, 6 and 7, for firmly anchoring the bit blade in the main body B; the fusible metal filling the interstices between the extension ends of the pins 45, and the openings of the main body in which they extend. In this connection the taper of the larger end of the pin 45 in the tapered openings 39 prevents the accidental removal of the pins 45, since there is a wedge fit of the fusible metal at this location, as is quite evident from Figures 6 and 7 of the drawings. The fusible metal is generally des-

ignated at 50 in the drawings. Where the fusible metal outlets on the exposed faces of the blade or main body, the same is chipped or machine flush with the adjacent surfaces.

In some instances, where water courses are provided longitudinally of the body of the bit structure, it may be necessary to protect such water courses against being sealed by the fusible metal. To this end, the drawings show longitudinally sloping water courses outletting at the upper end of the coupling shank 11 of the body B and also at the lower end of the body B at opposite sides of the slot 20, for depositing water or lubricating or washing fluid from the passageway of the drill stem 13 onto the blade C, for well known purposes. To prevent sealing of these water courses, since in some instances they may be cut by the openings 39 or 40, as shown in Figure 2, it is intended to place hollow tubes 60 therethrough, the exterior surfaces of which clear the walls through the body B, and in this clearance some of the fusible metal shown at 61 in the drawings is placed, either due to the placing of the fusible metal 50 above described, or in an auxiliary operation; thus insuring that the tubing 60 will prevent the water courses from being sealed; the tubing 60 extending from end to end of the body B.

From the foregoing description of the invention it is readily apparent that an improved article and method has been provided, which will prevent the bolts of bit blades from working loose, insuring that the blade will be attached to the main body against liability of loosening during a drilling operation.

Various changes in the shape, size, and arrangement of parts may be made to the form of invention herein shown and described, without departing from the spirit of the invention or the scope of the claims.

I claim:

1. In a device of the class described a supporting body having a socket therein with transverse openings intersecting at opposite sides of the socket, a blade having a transverse opening therein, an anchor pin secured in the transverse opening of the blade and extending at opposite sides of the blade through the socket and into the openings of the body which intersect the socket to prevent direct pull removal of the blade from the socket in the body, the blade and its anchor pin fitting in the slot and openings of the body with clearances, and a fusible bonding material capable of withstanding the usual drilling shocks filling said clearances and anchoring the blade and its pin rigidly in the body.

2. In a device of the class described a supporting body having a socket therein with transverse openings intersecting at opposite sides of the socket, a blade having a trans-

verse opening therein, an anchor pin secured in the transverse opening of the blade and extending at opposite sides of the blade through the socket and into the openings of the body which intersect the socket to prevent direct pull removal of the blade from the socket in the body, the blade and its anchor pin fitting in the slot and openings of the body with clearances, a fusible bonding material capable of withstanding the usual drilling shocks filling said clearances and anchoring the blade and its pin rigidly in the body, said anchoring material being metal fusible at a lower temperature than the material of the body or its anchor pin or the blade.

3. In a device of the class described a body having a socket therein with roughened walls, a blade having its outer surfaces roughened and facing the roughened walls of the socket in spaced relation therewith, and a fusible material capable of withstanding the usual drilling shocks anchored in spaces between the roughened faces of the blades and walls of the socket for rigidly anchoring the blade in said socket.

4. In a device of the class described a body having a socket therein with roughened walls, a blade having its outer surfaces roughened and facing the roughened walls of the socket in spaced relation therewith, a fusible material capable of withstanding the usual drilling shocks filling the spaces between the roughened faces of the blade and walls of the socket for rigidly anchoring the blade in said socket, said fusible material being metal which is fusible at a lower temperature than the tempering heat of the blade or body.

5. In a device of the class described a body having a socket therein with roughened walls, a blade having its outer surfaces roughened and facing the roughened walls of the socket in spaced relation therewith, a fusible material capable of withstanding the usual drilling shocks filling the spaces between the roughened faces of the blade and walls of the socket for rigidly anchoring the blade in said socket, said fusible material being metal which is fusible at a lower temperature than the tempering heat of the blade or body, and an anchoring pin transversely extending through the body and blade and secured thereto to prevent pulling of the blade from the body.

6. In a drill bit construction a body having a socket opening at the lower end thereof and transverse openings through the body intersecting the socket, a blade loosely seated in the socket having extensions at opposite sides thereof projecting into the openings which intersect the socket, and a fusible metal capable of withstanding the usual drilling shocks in the socket between the blade and socket walls and in the openings for rigidly seating the extensions therein.

7. In a drill bit construction a body having a socket opening at the lower end thereof and transverse openings through the body intersecting the socket, a blade loosely seated in the socket having extensions at opposite sides thereof projecting into the openings which intersect the socket, a fusible metal capable of withstanding the usual drilling shocks in the socket between the blade and socket walls and in the openings for rigidly seating the extensions therein, one of said extensions of the blade being tapered in one direction and the opening of the body in which it seats being tapered in an opposite direction whereby to anchor the same in a wedging relation in the fusible metal between them.

8. In a drill bit structure of the class described a body having a socket, a blade for loosely seating in the socket in spaced relation with the walls of the socket, the body having transverse openings thereacross opening at opposite sides and intersecting said socket, the blade having an opening for aligning with the above mentioned openings, a wedge pin driven into the opening of the blade and extending at opposite sides thereof into the openings of the body at opposite sides of the socket in loose relation in said body openings, and a fusible metal capable of withstanding the usual drilling shocks filling the spaces between the walls of the socket and the blade and in the openings of the body between the walls thereof and the ends of said pin.

9. In a drill bit structure a body having a socket at the lower end thereof, a blade for fitting in the socket loosely, a transverse bolt connecting the blade upon the body in seating relation in said socket, anchor pins rigid with the blade intersecting the body across said socket, and fusible metal capable of withstanding the usual drilling shocks filling the interstices between the blade and socket and about the anchor pins.

10. In a drill bit structure a body having a socket at the lower end thereof, a blade for fitting in the socket loosely, a transverse bolt connecting the blade upon the body in seating relation in said socket, anchor pins rigid with the blade intersecting the body across said socket, fusible metal capable of withstanding the usual drilling shocks filling the interstices between the blade and socket and about the anchor pins, said body having passages therethrough, protecting tubes fitting in spaced relation in the passages, and fusible metal anchoring the tubes rigidly in the passages to provide water courses.

11. In a drill bit construction the combination of a holder having a slot opening at the lower end thereof and opening at a side thereof, a drilling blade disposed within said slot and movable into the slot or out of the slot through the side opening of the slot upon the holder, means positively connecting the

blade with the holder against dropping from said slot, the blade where it fits in said slot having certain clearance spaces between the same and the walls defining the slot, and a fusible bonding material cast in said clearance spaces and firmly anchoring the blade fixedly in the holder against vibration.

12. In a drill bit construction the combination of a supporting holder having the lower end thereof bifurcated to provide a bottom opening slot extending transversely across said holder and opening at opposite sides thereof, and a drilling blade having a portion thereof disposed within said slot so that the sides of said portion extend beyond the sides of the holder exteriorly of the slot, means positively connecting the blade upon the holder to prevent dropping of the blade by gravity from the holder when in operating position, and metal having a fusion point lower than that of the blade or holder cast in the slot between the portion of the blade which is in the slot and the walls of the holder defining said slot and firmly anchoring said blade upon the holder to prevent vibration thereof as an incident of drilling.

13. In a drill bit construction the combination of a holder having a socket opening at the lower end thereof, a drilling blade loosely seated in the socket, interfitting portions upon the blade and socket connecting the blade to the holder against dropping therefrom when the same are in drilling position, and a readily fusible metal cast in the socket between the blade and socket walls and firmly anchoring the blade to the holder for preventing vibration of the blade in the holder during drilling.

14. In a drill bit construction the combination of a holder having a socket opening at the lower end thereof, a drilling blade loosely seated in the socket, interfitting portions upon the blade and socket connecting the blade to the holder against dropping therefrom when the same are in drilling position, a readily fusible metal cast in the socket between the blade and socket walls and firmly anchoring the blade to the holder for preventing vibration of the blade in the holder during drilling, and a retaining bolt extending transversely through the holder and blade for supporting the latter upon the holder.

J. C. STOKES.
